LIFTING DEVICE

Samuel G. Jones, Norfolk, Va., assignor to Berkley Machine Works & Foundry Co. Inc., Norfolk, Va., a corporation of Virginia

Application September 16, 1929, Serial No. 393,021

16 Claims. (Cl. 254—93)

This invention relates to lifting devices and, more particularly, to a device for lifting automobiles from the ground to an elevated position where they may be conveniently inspected and 5 lubricated.

The principal object of my invention, generally considered, is to provide an improved lifting device particularly adapted for raising automobiles in which shock incident to arresting the raising 10 of the device is obviated, and the device brought to rest automatically at a desired position.

Another object of my invention is to provide a lifting device particularly adapted for raising automobiles and provided with safety means for 15 locking the device in elevated position and preventing it from dropping in case the fluid pressure raising means should fail.

A further object of my invention is to provide a fluid pressure operated automobile lifting device 20 comprising a vertically movable plunger, a runway support, and runways mounted on the ends thereof with air line connections extending from the plunger to both sides of the runways so that the device may be operated from either 25 side.

A still further object of my invention is to provide an automobile lifting device with runways adapted to support the wheels of automobiles and devices connected to said runways for 30 safety and convenience and connection with the support of and servicing of automobiles on the device.

Other objects and advantages of the invention relating to the particular arrangement and construction of the various parts will become apparent as the description proceeds.

Referring to the drawings illustrating my invention, the scope whereof is defined by the appended claims:

40 Figure 1 is a side elevation of an embodiment of my lifting device in lowered position, the outer cylinder and foundation of said device being shown in vertical section.

Figure 2 is a plan of the device shown in Figure 1.

Figure 3 is a fragmentary transverse sectional view on the line 3—3 of Figure 2, looking in the direction of the arrows.

Figure 4 is a fragmentary side elevational view 50 of the device in raised position.

Figure 5 is a fragmentary view of the lower end of the plunger and adjacent portions of the cylinder when the plunger is approaching its uppermost position.

55 Figure 6 is a view corresponding to Figure 5

showing the plunger after the flow of liquid between it and the cylinder has been cut off by the stuffing box.

Referring to the drawings in detail, like parts being designated by like reference characters, 60 there is shown an automobile lifting device 1 comprising an outer cylinder 2 with its lower end preferably embedded in a concrete foundation 3 and its upper end likewise embedded in a concrete foundation 4, said foundation 4 preferably 65 being extended to provide a base or floor 5 for supporting the automobile runways 6.

The outer cylinder 2 is preferably closed at its lower end, as indicated at 7, so as to serve as a container for liquid 8 such as light oil which will 70 not congeal in cold weather. At the upper or open end of the cylinder 2 is, in the embodiment illustrated, packing means such as a stuffing box 9 adapted to close the space between the outer cylinder 2 and an inner cylinder or hollow 75 plunger 10, said plunger having a closed bottom and constituting a reservoir for lifting liquid. To avoid leakage between the stuffing box and the inner cylinder or plunger 10, a gland 11, connected by bolts or nuts 12 and 13 to said stuffing box, 80 is preferably employed with associated packing, as shown. The cylinder 2 is assembled with the plunger 10, which has a head 14 flanged as at 15 beyond said plunger, before the stuffing box 9 is applied, so that when said stuffing box 9 is connected to the cylinder 2, it forms a shoulder 16 adapted to be engaged by the flanged portion 15 of the head 14 and limit movement of the plunger 10 away from the cylinder 2. The plunger 10 is formed with one or more apertures or perforations 17 preferably disposed a short distance above or away from the flanged portion 15 of the head 14 for a purpose to be hereinafter described. 85 90

The stuffing box 9 and its associated cylinder 2 are preferably secured to the foundation 4 by 95 bolts 18 extending from embedded angle irons 19 through the upper flanges 20 on the stuffing box, the nuts 21 on said bolts being subsequently tightened to securely hold the stuffing box and cylinder in place. The foundation 4 is preferably 100 formed with a pocket 22 above the stuffing box leading to a drainage passage 23 for preventing the accumulation of water or other liquid around the stuffing box and plunger.

Preferably connected to the top of the plunger 105 10 is a member or casting 24 to which is connected, in any desired manner, a runway support 25, said support being desirably in the form of a channel 26 with an upper web 27 and depending flanges 28. Said channel is desirably reinforced 110

on one side by an angle iron 29, and preferably connected to the other side is a safety device 30 in the form of a strut 31 pivotally mounted on an operating rod 32 which may be, in turn, supported in angle iron clips 33. Said strut 31 may be in the form of a channel iron with braces 34 extending from intermediate portions thereof to the operating rod 32. The operating rod 32 is desirably formed with a crank 35 adapted to engage one of the braces 34 for lifting or moving the strut 31 to inoperative position and an arm 36 adjacent the side of the device for operating the crank 35. If desired, the rod 32 may be extended to the other side of the device and provided with a similar operating arm at that side so that it may be operated from either side.

Mounted on each end of the runway support is an automobile runway 6, said runways being disposed parallel to one another and being spaced 20 to receive and support the wheels of an automobile. Each runway 6 is preferably formed as a channel 37 with a lower web 38 and upstanding flanges 39, the webs of the channels 27 and 37 being desirably connected together as by riveting 25 so that the runways are firmly mounted on the runway support. Connection between these channels is desirably reinforced by the angle iron 29 heretofore referred to and by short pieces of angle iron 40 on the other side of the runway support 25, the corresponding flanges of said angle irons being respectively connected to the adjacent portions of the runway support and runways.

The runways 6 are desirably reinforced adjacent their intermediate portions by angle irons 41 with vertical flanges 42 connected to the upstanding flanges 39 of the runways 6 and the horizontal flanges 43 extending outwardly. The portions of the angle irons 41 immediately over the runway support 25 are preferably disposed at 40 a maximum elevation and those portions of the angle irons on either side thereof slope both ways preferably to the level of the upper edges of the flanges 39 of said runway to most efficiently reinforce the same. At each end of each runway 45 is desirably mounted a ramp 44 which is preferably in the form of a channel with an outer end flaring, as indicated at 45, and the inner end pivoted to the adjacent end of the runway or an angle iron or hinge casting 46 thereon as by means of a pivot pin 47 passing through hinge 50 lugs on the runway and ramps respectively.

In order to lock the automobile in place on the runways, adjustable chocks 48 are desirably provided and formed as castings 49 fitting on the flanges 39 of the runways and provided with chocking members 50 preferably in the form of inverted U shaped rods which are movable from inoperative positions, indicated at the left of Figure 2, to operative positions, shown at the right of Figure 2, where said chocking members are locked in operative positions between upstanding lugs 51 of the chocks. In order to conveniently support a bucket or other device for catching spent oil or other fluid from an automobile, a bucket holder 52 is desirably adjustably mounted on one of the runways as by means of a clip 53 fitting over a flange 39 of a runway. The bucket holder is pivotally mounted in the clip, as illustrated, and the clip is slidable along the flange so that a bucket 54 may be supported in any desired position.

In order to effect the raising and lowering of the plunger and associated runways, the cylinder 2 and plunger 10 are desirably filled with light oil 8 which does not congeal in cold weather as

by means of the filling opening 55 closed by a plug 56, so that when the plunger is in its lowermost position, the oil is at a level of about six inches below the filler plug. In order to supply the power for causing the raising of the plunger, air pipes 57 are preferably connected to the plunger adjacent the upper end thereof and extend to either side of the lifting device, an operating valve 58 being placed in the line which connects with an air hose or connection to a source of compressed air, and an exhaust valve 59, which permits release of the air pressure in the plunger 10, provided.

The operation of my lifting device heretofore described is as follows. With the runways and connected mechanism in the position illustrated in Figure 1, the automobile or other device to be lifted may be run up on the runways 6 and the chocks 48 moved to locked position shown at the right of Figure 2, so that in case the hand brake of the car is defective, the automobile will not run off the runways. One of the operating valves is then turned on after connection with an air line, all of the other valves, of course, being closed. This causes compressed air to enter the top of 100 the plunger 10 and displace or force the oil or other lifting liquid or fluid 8 from the plunger 10 through the aperture or apertures 17, in the head or head portion of the plunger 10, to the cylinder 2 below the bottom or head 14 of the plunger, 105 causing said plunger and supporting runways to be raised. When the plunger reaches the position with respect to the cylinder, indicated in Figure 5, the lower end of the stuffing box or packing means approaches closely the apertured portions 110 115 118 122 Having now described my invention, I claim:

1. In a lifting device, a cylinder, a plunger operating therein, liquid in said cylinder and plunger, the end of said plunger in said cylinder being

- apertured, means for forcing said liquid from said plunger to said cylinder through the apertured portion thereof, and means to close said apertured end of the plunger to check the flow of liquid prior to the end of the stroke. 5
2. In a lifting device, a cylinder, a piston with a headed portion therein, a shouldered portion on the cylinder outwardly of said headed portion and adapted to limit outward movement of said headed portion, fluid in said piston and cylinder for operating said piston means normally permitting a flow of fluid between said piston and cylinder, and means for automatically cutting off the flow of fluid from the piston to the cylinder prior to engagement between said headed and shouldered portions. 10
3. In a lifting device, a pair of telescoping cylinders, liquid in said cylinders, the head of the inner cylinder being perforated to allow said liquid to pass from one to the other, and means on said outer cylinder to close the perforated portion of said inner cylinder and cut off the flow of liquid at a predetermined position. 15
4. In a lifting device, a pair of telescoping cylinders, the inner cylinder having its end received in the outer cylinder and closed by a head extending beyond the body of said cylinder, said outer cylinder being formed with a stuffing box closing the space between the bodies of said inner and outer cylinders, the inner end of said stuffing box forming a shouldered portion adapted to engage the outwardly extending portion of the head of the inner cylinder, said inner cylinder being perforated outwardly of and adjacent said head for permitting fluid to pass from said inner to said outer cylinder when the device is operated, said stuffing box serving to close the perforated portion of said cylinder prior to engagement between said head and stuffing box. 20
5. In a lifting device, an outer cylinder, an inner cylinder telescoping therewith, a stuffing box closing the space between said cylinders, said inner cylinder being formed with a head closing its inner end and projecting beyond the walls thereof, said inner cylinder being perforated some distance from said head so that liquid flow between said cylinders is cut off by the stuffing box prior to engagement between said head and stuffing box. 25
6. An automobile lifting device comprising a foundation, an outer cylinder opening upwardly and embedded in said foundation, a stuffing box adjacent the upper end of said cylinder, a plunger fitted in said cylinder and adapted to move in said stuffing box, an automobile supporting runway mounted on the top of said plunger, fluid contained in said cylinder and plunger, means normally permitting fluid to flow from the plunger to the cylinder, means for applying pressure to said fluid to raise said plunger and runway, and means to check the raising of the plunger prior to engagement between the end thereof and the stuffing box by automatically cutting off the flow of fluid from said plunger to said cylinder. 30
7. An automobile lifting device comprising an outer cylinder opening upwardly, a stuffing box adjacent the open end of said cylinder, a hollow plunger fitted in said cylinder and formed with a head below said stuffing box and adapted to limit upward movement thereof, an automobile supporting runway mounted on the top of said plunger, liquid contained in said cylinder and plunger, a connection to said plunger for applying compressed air on top of said liquid to force liquid from the plunger to said cylinder and raise the plunger, said plunger, for that purpose, being apertured adjacent its lower end, said apertured portion being disposed above the head of said plunger, whereby the flow of liquid is cut off by the stuffing box prior to engagement between the head of the plunger and said stuffing box, so that impact between the head and stuffing box is avoided. 35
8. An automobile lifting device comprising a plunger mounted for vertical movement, an automobile supporting runway mounted on the top of said plunger, a connection to said plunger for supplying compressed air to raise it, a strut adapted to be swung to vertical position for supporting said plunger and runway if the air supply fails or rotated to horizontal position beneath the runway for permitting said plunger and runway to be lowered, and an operating rod for said strut, said strut being pivotally mounted on said rod, said rod being extended beneath the runway to the side thereof and provided with an arm for manual operation thereof, and a crank for controlling said strut. 40
9. An automobile lifting device comprising a vertically movable plunger, a support mounted on the top of said plunger, and a pair of automobile runways mounted on each end of said support and spaced for receiving the wheels of an automobile, said runways being generally channel shaped in section with a lower supporting web and upstanding flanges, the intermediate portions of said runways being trussed by angle irons with vertical flanges connected to the upstanding flanges thereof and horizontal flanges extending outwardly therefrom, said angle irons being bent so that the portions thereof above the runway support are at a maximum elevation with the ends sloping both ways to approximately the level of the tops of the channel flanges. 45
10. An automobile lifting device comprising a vertically movable plunger, channel shaped runways connected to the top of said plunger for being raised and lowered thereby, said runways having lower webs adapted to support the wheels of an automobile and upstanding flanges adapted to guide said wheels, and chock means comprising connecting devices mounted on one of said flanges and chocking members adapted to be rotated on said connecting devices to block the channel, and lug means on said connecting devices for locking said chocking members in operative positions. 50
11. An automobile lifting device comprising a vertically movable plunger, channel shaped runways connected to the top of said plunger for being raised and lowered thereby, said runways having lower webs adapted to support the wheels of an automobile and upstanding flanges adapted to guide said wheels, a clip fitting over a flange of one of said runways and slidably therealong, and means pivotally mounted on said clip for adjustably supporting a bucket between said runways. 55
12. A vehicle lifting device comprising an outer cylinder opening upwardly, a stuffing box adjacent the upper end thereof, a plunger fitting in said cylinder and adapted to move in said stuffing box, a supporting runway mounted on the top of said plunger, fluid contained in said plunger and cylinder, the head of the plunger being perforated to allow said fluid to pass between said plunger and cylinder, and means on said cylinder to close the perforated portion of the plunger and cut off the flow of fluid at a predetermined position. 60

13. A vehicle lifting device comprising a cylinder opening upwardly, a plunger fitting in said cylinder and adapted to reciprocate therein, and a supporting runway mounted on the top of said plunger, fluid contained in said cylinder and plunger, said plunger having a head extending beyond its body, said cylinder having a stuffing box closing the space between it and the body of the plunger, the inner end of said stuffing box forming a shoulder adapted to engage the head of said plunger, said plunger being perforated adjacent its head for permitting fluid to pass from it to said cylinder when the device is operated, said stuffing box serving to close the perforated portion of the plunger prior to engagement of the head therewith.

14. A vehicle lifting device comprising an outer cylinder opening upwardly, an inner cylinder fitting therein and adapted to reciprocate with respect thereto, a vehicle supporting runway mounted on the top of said inner cylinder, and fluid contained in both of said cylinders, said inner cylinder having a head closing its lower end and projecting beyond the walls thereof, that portion of said inner cylinder adjacent said head being perforated so that said fluid may pass between said cylinders, said outer cylinder having

an annular member closing the space between the cylinders and adapted to cut off said liquid flow prior to engagement between it and the head of the inner cylinder.

15. In a lift device, a cylinder, a tubular plunger therein having a closed bottom and constituting a reservoir for lifting liquid, packing means at the upper end of said cylinder surrounding said plunger, means for displacing lifting liquid from said plunger, said plunger having an opening through which said lifting liquid is discharged into said cylinder when so displaced, said opening being spaced above the bottom of said plunger whereby it is covered by the packing means and the flow of liquid out of the plunger cut off while a substantial part of the lower end of said plunger still remains in said cylinder.

16. In a lifting device, a pair of telescoping cylinders, liquid in said cylinders, the head of the inner cylinder being perforated to allow said liquid to pass from one to the other, and means to close the perforated portion of said inner cylinder and cut off the flow of liquid at a predetermined position.

SAMUEL G. JONES.
